(57) CLAIM

The ornamental design for an earstem portion for eyeglasses, as shown and described.

DESCRIPTION

FIG. 1 is a left frontal perspective view that shows an embodiment of the design incorporated in illustrative eyeglasses, including an illustrative speaker housing obscuring a portion of the design;

FIG. 2 is another left frontal perspective view that shows an embodiment of the design incorporated in illustrative eyeglasses;

FIG. 3 is a left side elevation view showing an embodiment of the design incorporated in illustrative eyeglasses, this view being reduced in scale and showing the eyeglasses in use by a wearer, with an illustrative speaker housing obscuring a portion of the design;

FIG. 4 is a left side elevation view;

FIG. 5 is a front elevation view;

FIG. 6 is a rear elevation view;

FIG. 7 is a right side elevation view;

FIG. 8 is a top plan view; and,

FIG. 9 is a bottom plan view.

The broken lines shown in FIGS. 1-9 are for illustrative purposes only.
